INVENTOR.
WILFRED DUPRÉ

BY

William E. Baff ATTORNEY.

UNITED STATES PATENT OFFICE.

WILFRED DUPRÉ, OF WORCESTER, MASSACHUSETTS.

DUSTPAN.

1,392,406.

Specification of Letters Patent.

Patented Oct. 4, 1921.

Application filed February 17, 1921. Serial No. 445,632.

To all whom it may concern:

Be it known that I, WILFRED DUPRÉ, a citizen of the United States of America, and a resident of the city of Worcester, in the 5 county of Worcester and State of Massachusetts, have invented new and useful Improvements in Dustpans, of which the following is a specification.

This invention relates to improvements in 10 receptacles and more particularly to means for operating the lids of dust pans.

One of the objects of my invention is to provide an improved dust pan that shall be equipped with a simple attachment to allow 15 the lid of the dust pan to automatically close in the act of lifting the dust pan from contact with the floor.

Another object of my invention is to provide a simple, inexpensive and highly efficient device of this character wherein the 20 cover plate is so arranged and mounted as to normally, when the dust pan is lifted from the floor, close thus preventing the dust in the pan from spreading about the room and 25 becoming infectious to the operator of the dust pan, the arrangement and action of the parts being such that the moment the dust pan is brought into engagement with the floor or other surface the lid will automatically 30 fly open thus allowing the operator to sweep dust therein.

A still further object of my invention consists in the provision of a simple and instantaneous operating attachment to a dust 35 pan that enables the lid of the dust pan to be controlled by a trigger carried by this lid, this trigger acting as a means for opening the lid when the trigger is depressed and of closing this same lid through gravity 40 when the trigger is free to fall as will happen when the dust pan is lifted out of contact with the floor.

With the above and other objects in view my invention consists in the combination, 45 arrangement and details of construction disclosed in the drawings and specification, and then more particularly pointed out in the appended claims.

In the drawings wherein similar reference 50 characters designate similar parts throughout the respective views thereof,

Figure 1 is a front elevation of the dust pan equipped with my improvement, the lid being shown in open position,

55 Fig. 2 is a side elevation of Fig. 1,

Fig. 3 is a front elevation of my device showing the lid in closed position,

Fig. 4 is a side elevation of Fig. 3,

Fig. 5 is a top plan view of the dust pan,

Fig. 6 is a bottom plan view of the dust 60 pan, and

Fig. 7 is a fragmental sectional elevation of a part of my invention showing the attachment of handle to dust pan.

Referring to the drawings which are 65 merely illustrative of my invention 1 designates the dust pan which may be of any suitable design and construction but is preferably of the shape shown in the present drawings. The dust pan is open at its front portion as is indicated at 9, and the front edges of the sides of this pan are inclined as at 2 and slope upwardly, the bottom edges 3 joining the edges 2 also sloping upwardly at a lesser angle, forming the shoulders 4 as 70 shown clearly in Fig. 4.

The bottom of the dust pan is designated 5 and is flat as shown in the drawings. There is a cover plate or lid 6 which is hingedly mounted as at 8 upon the pan in a manner to close the open front portion of this pan. The top portion of the pan is designated 7 and is also preferably flat. The side walls A and B of the dust pan preferably incline in opposite directions as clearly illustrated in Fig. 5. The lid 6 is formed at its opposite ends and at its inner plane with the lugs 10 formed at right angles thereto and in parallel relation to each other, these lugs being suitably perforated to receive the 85 pins 11 which are formed or bent upon a substantially U-shaped member or bail, the pins 11 being particularly formed upon the side arms 12 of this bail which are suitably guided for vertical movement in the guide 90 lugs 14 also formed outstanding upon the inclined lower edges 3 of the dust pan, the bottom cross-piece of this U-shaped member or bail being designated 15 and extending longitudinally under the dust pan 1. If desired the upstanding terminal 13 may be 100 formed upon the pins 11 and are adapted with the pins 11 to provide abutments for the lid 6 to rest against when the latter reaches upright open position, and when in 105 this position the abutments assure that the lid will be under the influence of gravity the moment the dust pan is lifted out of contact with the floor in a manner to be described.

It will be noticed that the U-shaped bail or member is guided in a vertical plane and is suspended upon the lid and owing to its weight the lid is held in closed position as soon as it rests upon the inclined edges 2 of the dust pan.

It will now be seen that the pull exerted by the U-shaped member or trigger 15 is such as to force the lid or cover plate downwardly upon its seat, as long as the tread 15 of this member is out of contact with the floor surface. In the act of using the dust pan the operator forces the tread 15 of the trigger member or bail down in contact with the floor and when this is done the dust pan moves down relatively to the bail and this makes the upper ends of the bail move upwardly above the lower end of the dust pan and in doing so the pins 11 will force the lugs 10 of the cover plate upwardly serving as cranks and thereupon the lid 6 will move upwardly as far back as the pins 11 permit and the correct position of the lid when up-raised is shown in Fig. 2, it being noticed that as long as the dust pan rests upon the floor the trigger tread 15 also rests upon the floor and the lid is in full wide open position and the operator may then sweep in the dust into the pan the same as is now done in connection with any pan. The moment it is desired to lift the dust pan and place it in another position the pan when lifted allows the weight of the bail and cover plate or lid to act and the cover plate will then close keeping the dust from coming out of the pan and thus enhancing the sanitary feature of this device.

I design to secure the handle 16 in position as follows: I form a depending tube 22 which is slit throughout its diameter thus providing a resilient spreadable portion for taking a good bite or hold upon handles of various diameters. The handle fits this tube projecting downwardly into the dust pan and rests on top of the countersunk portion 20 into whose recess 19 the head of a fastener 21 projects, this fastener being a screw which is then tapped directly into the bottom of the handle 16 and binds this handle down tight upon the portion 20 countersunk into the bottom of the dust pan. This handle thus is made to stand out vertically

from the bottom of the dust pan and is removable by simply removing the screw or other fastener. Numerous changes in design may be made without departing in principle from the details of construction herein disclosed.

What I desire to claim and protect by Letters Patent is:—

1. A device as described consisting of a dust pan having its front end open, a cover plate hingedly mounted upon said dust pan so as to normally close said front open end, a substantially U-shaped member connected pivotally at its upper end to said cover plate, and having its cross-rod projecting below and out of contact with the bottom of said pan, the side arms of said U-shaped member straddling said dust pan, and guides 70 for said side arms upon the sides of said pan, said cross-rod adapted to be moved upwardly in order to cause said cover plate to be thrust to open position.

2. A device as described consisting of a 75 dust pan having its front end open, a cover plate hingedly mounted upon said dust pan so as to normally close said open front, lugs formed at right angles of said plate at opposite ends, a handle secured to said dust pan, 80 a U-shaped bail trunnioned in said lugs and having its cross-piece projecting movably beneath said dust pan, said cover upon the depression of said bail adapted to fly open, and stops for limiting the movement to open 85 position of said cover plate for holding it under the influence of gravity.

3. A device as described consisting of a dust pan having an open front, a lid hingedly connected to said dust pan and adapted to close said open front, lugs on said lid at opposite ends, a U-shaped bail straddling said pan and projecting below said pan when the lid is closed, cranks upon said bail trunnioned in said lugs, and guide lugs for 95 guiding the vertical movement of said side arm of said bail.

In witness whereof I have hereunto set my hand and affixed my seal this 26th day of June, 1920.

WILFRED DUPRÉ. [L. S.]
